(57) **CLAIM**

The ornamental design for a castle-shaped handheld electronic game, as shown and described.

DESCRIPTION

FIG. 1 is a front perspective view of a castle-shaped handheld electronic game showing an exemplary embodiment of the design;

FIG. 2 is a rear perspective view thereof;

FIG. 3 is a right side perspective view thereof;

FIG. 4 is a left side perspective view thereof; and,

FIG. 5 is a top perspective view thereof.

The bottom of the design is flat and unornamented.
